HOTBED FRAME

Eugene P. Leeper, Bristol, Pa.

Application April 16, 1940, Serial No. 329,851

10 Claims. (Cl. 47—19)

This invention relates to hotbed frames.

Hotbed frames are of considerable antiquity so far as the broad principles are concerned. The provision of a frame rising perpendicularly from the ground and defining an upper sloping glass covered opening is well established. The previous practices in this regard have caused the creation of various sorts of sashes with which the opening of the frame could be closed as completely as possible while still permitting crude manipulations to approximate a certain degree of ventilation when desired. It has been found most expedient heretofore to provide a series of light transmitting sashes which were individually laid over the opening and held down as best they could be with make-shift weights and the like and when ventilation or access to the frame was necessary had to be tilted or propped up by awkward accessories. The difficulty with most of the prior efforts starts with a fundamental that they must be cheap or else they will make shift of whatever is offered that is cheaper. In the case of the individual sashes arranged for tilting or propping open, as are the great body of hotframe sashes in use today, there are many cases in which they fail for one reason or another and the budding shoots are ruined, so that the entire benefit of the early work with the hot frames is lost.

The disadvantages of the prior frames with which I am most particularly familiar, and in view of which the hotbed frame of the present invention was evolved and invented, may be summarized as follows; first is their susceptibility to damage from sudden wind storms. Many cases can be given in which entire sashes have been lifted bodily from the hotbed frame and whirled high in the air to the ultimate destruction of the glass and most of the frames. This is most certainly an added factor with the conventional propping arrangements by which in effect tunnels are created by adjacent sashes facilitating adverse wind effects. To guard against this many expedients have been resorted to, as by laying heavy stones on the sashes, or overlying a plurality of them with a long pipe which was fastened down at the ends, or by tying down the individual sash, and the like. Second, owing to the general arrangements, and the wind protection of the past to prepare the hotbed frame for ventilation was a two man job, one to work on each side of the frame, to help tilt and to prop, etc. Third is the factor of too much shade area. It has been customary to provide transverse girders or the like upon which the

edges of adjacent sashes could lie in some hope of preventing the rain from running into the frame, and such broad girders every few feet (three) not only prevent the proper working of the bed but cast too much area of shade. Fourth is the problem of water, and especially of rain. Owing to warping and other adverse effects of prior constructions it has been practically impossible to cause the water to run off and not into the bed. The openness of the bed and of the cracks between sashes even with girders, has permitted grave loss of seeds and plants through water seepage.

Some of the objects of the present invention are to provide an improved hotbed; to provide a hotbed wherein the contents of a hotbed are protected from rain, snow and bad weather conditions generally; to provide a hotbed wherein provision is made to automatically compensate for expansion, contraction and warpage of hotbed sashes; to provide a novel setting means for the light panes of a hotbed sash; to provide a hotbed having sashes which are so arranged as to fully cover the bed frame but are adjustable as to position to give full access to the bed proper wherever necessary to plant, cultivate or otherwise work within the frame; to provide an interlocking means for hotbed sashes which completely stabilizes one sash with respect to another and eliminates the danger of the sash being dismantled by wind; and to provide other improvements as will hereinafter appear.

In the accompanying drawings Fig. 1 represents a plan of a hotbed frame embodying one form of the present invention; Fig. 2 represents a section on line 2—2 of Fig. 1; Fig. 3 represents a section on line 3—3 of Fig. 1; Fig. 4 represents a section on line 4—4 of Fig. 1; Fig. 5 represents an enlarged detail section on line 5—5 of Fig. 1 showing the initial assembling position of the parts; Fig. 6 represents a perspective of one unit of a hotbed frame embodying the present invention and showing one arrangement of the sash for ventilation or access purposes but with the glass omitted in order to illustrate the ledge construction; and Figs. 7, 8 and 9 represent respectively sections through abutting pairs of stiles, each showing a different modified form of scupper.

Referring to the drawings one form of the present invention comprises a frame 10 preferably rectangular in shape and having an open top and bottom, the former for access to the interior and the latter for access to the soil in which seeds and plants are to be propagated. The rear wall of the frame is higher than the 55

front wall so that there is a well defined pitch or incline provided for the superposed sash to carry off rain water. In the present description one unit of the frame only will be described but it is to be understood that generally several units will be assembled end to end and suitably interconnected to form a relatively long hotbed.

Preferably each unit includes a plurality of cover control sashes, each formed of two parallel stiles 11 and 12 interconnected near the adjacent pairs of ends respectively by rails 13 and 14 so that a strong four sided sash results. Since the sash so formed is relatively wide it is preferred to subdivide the light opening and as here shown 15 two longitudinally arranged mullions 15 and 16 interconnect the rails 13 and 14 to thus form three light openings each of a size to accommodate a pane of glass 17 of substantial area but yet one unlikely to fracture in ordinary handling 20 of the sash. In connection with the rails 13 and 14, and mullions 15 and 16 it should be noted that the upper faces of the stiles 11 and 12, the rail 13, and the mullions 15 and 16 all lie in the same plane, while the rail 14 is below that plane. 25 Hence since the rail 14 is designed for location at the front, or low point, of the frame 10, it will be evident with the panes of glass 17 in place that water will run freely off that end of the sash. It will also be observed that the respective 30 glass supporting ledges 18 are formed respectively only on the inner walls of the stiles, mullions and rail 13 and that the upper faces of such ledges are in the same plane as the upper face of the rail 14. The glass panes are therefore of such 35 a length as to overlap and seat upon the rail 14. The mullion ends which abut the rail 14 are properly rabbeted to overlie the rail 14 and thus provide continued lateral contact with the portion of the glass panes which overlap the rail 14 and also prevent water from reaching the 40 lower transverse rail joint.

One feature of the present invention embodies a novel means for setting the glass panes 17 in the respective sash openings, and this comprehends the provision of a slot 20 as a boundary 45 for the respective ledges 18 to receive putty 21 in excess of that normally required to set a pane of glass. In assembly of the respective panes, the putty is filled in the slot 20 and overlies the upper face of the ledges 18, the preferred method 50 of application being by the use of a pressure gun which is caused to follow the path of the ledges exuding the desired amount of putty. A pane is then laid upon the annular strip of putty, pressed 55 firmly into contact therewith, and then anchored by driving glazier points 22 laterally into the adjacent stile, rail or mullion to remain overlapping the marginal edge of the glass pane. This overlapping relation of one sash side to another 60 coupled with the bisected inclined joint faces insures gravitationally secured joints for interconnecting pairs of sash.

To assist in the draining of the upper faces of the stiles 11 and 12 each is provided with a longitudinally disposed gutter 23 extending from one end to the other.

For the purpose of interconnecting one sash with another and also with the frame 10, the stile 11 has its top provided with a substantially V-shaped groove 24 extending throughout the length thereof. Preferably the face of this groove 24 nearest to the center line of the stile is vertical while the opposite face is inclined outwardly and upwardly to meet the outer face of the stile and 70 thus form a coupling lip lying well below the top

of the stile. The opposite stile 12 has its bottom provided with a substantially V-shaped groove 25 of a depth similar to that of groove 24 extending throughout the length thereof. Preferably the face of this groove 25 nearest to the center line of the stile is vertical while the opposite face is inclined outwardly and downwardly to meet the outer face of the stile and thus form a coupling lip lying well above the bottom of the stile. The contour and size of the grooves 24 and 10 25 are complementary so that when the lip on the stile of one sash is fitted into the complementary lip on the stile of the next adjacent sash, there will be an effective interlock provided between the two sashes. In order to insure that all of the 15 sash in a series have their outer surfaces lying substantially in common planes, it is important that the upwardly presenting lip surface 24 and the downwardly presenting groove surface 25 have their sloping faces as duplicate complements 20 wherein each sloping face cuts across a plane median of each sash. In connection with the interlocking of the aforesaid lips it should be noted that it is preferable to round off the edge of the lip formed by the groove 25 so that when 25 it interfits with its groove 24, a scupper 26 is provided running the length of the stile and by reason of the inclined position of the sash will carry water rapidly away.

For assembling the sash with the frame in interconnected sliding relation, one end of the frame 10 has a retaining strip 27 fixed thereon by nails 28 or other fastening means, such strip having a substantially V-shaped groove 30 cut at the inner side of its bottom face to extend 35 throughout the length of the strip 27. The groove 30 is generally complementary to the groove 24 so that while a relatively free sliding movement of the sash can take place, the inclined meeting surfaces of the interfitted lips holds the sash against 40 vertical displacement. At the opposite end of the frame a second retaining strip 31 is secured transversely of the frame being held by nails 32 or like fastening means. The inner side of the top of the strip 31 is so cut as to form a substantially V-shaped groove 33 running lengthwise 45 of the strip for complementary interfitting with the groove 25 and lip on the adjoining sash. Thus while a free sliding movement of the sash relative to the strip 31 is permitted the weight 50 of that sash plus the downward pressure of the next adjacent sash securely holds the parts together.

That the foregoing assembly may result in the desired sealed joint between contiguous sections 55 regardless of the effects of expansion or contraction, the unit is put together in an ingenious way. First the rail 27 is fastened in place at the left end of the frame as viewed from the front and the first sash section A joined thereto by interlocking the lips and grooves 24 and 30 respectively. Section B is then placed in position with its groove 24 and its lip substantially registered vertically below the groove 25 and its lip, but actual interfitting is prevented by placing wedges 65 of suitable thickness between the opposed side faces of the two sections A and B. As a result the stiles 12 and 11 are initially spaced as shown in Fig. 5 with the wedge in dotted lines. The same wedge operation is repeated between sections B and C and between section C and the rail 31, which latter can now be fixed to the frame 60 10. All the wedges are now removed and the weight of each sash allows the respective grooves 25 to ride downwardly upon the inclined face 70 75.

of the grooves 24 to thus form a rigid interlock but one which can respond as an automatic adjustment to take up contraction or relieve expansion while always maintaining a sealed guide joint.

In Figs. 7, 8 and 9 three different forms of scuppers are shown to carry off any water entering between the joint of adjacent stiles. Thus in Fig. 7 the scupper 34 is arc shaped in cross section and cut lengthwise of and at the lower end of the inclined face which forms one side of the groove 24. In Fig. 8 the scupper 35 is also arc shaped in cross section but is cut lengthwise of and at the lower end of the vertical face which forms one side of the groove 24. In Fig. 9 the scupper 36 is similarly located with respect to the scupper of Fig. 8, but is substantially rectangular in cross section. All such scuppers serve to prevent collection of water at the joint and are effective to eliminate ice in the joint.

From the foregoing it will be apparent that a complete unitary hotbed frame has been devised producing a result not heretofore attained by any prior sash frames. These advantages may be summarized as follows: The sashes resting upon the frame members to cover the opening of the hotbed are interlocked with a lateral guide member, so far as the first sash of the series is concerned so that the side engaging therewith is held down while still permitted to slide relative to the guide. The other edge of the first sash rests upon the complementary upwardly presenting edge of the contiguous sash so as to impose its weight thereon to both hold the sash down and cause it to continue to remain interlocked.

The inclined abutting faces of the overlapping portion (Fig. 5) causes a lateral thrust to be developed by the sheer weight of the imposed sash so as to form a rather rigid joint (so far as torque is concerned at the point of meeting) and which also causes the sash to pull together laterally thus maintaining tight engagement of the entire series of sashes along the hotbed frame. With the sashes thus disposed a single operator can slide any given sash or sashes in one direction or another relative to the hotbed (normal to the longitudinal center of the hotbed) so as to uncover large areas of the opening formed between frame members to permit the utmost in ventilation and while maintaining interlocked weighted mutually guiding relation so that the sashes in due course can be slid back to close the openings.

The advantages of this construction are so important that they cannot be overemphasized. It reduces the shade area by eliminating cross girders, it provides a lock joint which maintains despite attempts at warping, it keeps the sash from blowing off under high wind conditions and therefore saves glass, the interlocking joint makes a rail which is approximately four times stronger than any former constructions, the sash frames mutually reinforce each other to minimize sag or warp, it prevents freezing of the sash together by maintaining a constantly tight joint between adjacent sashes, by opening one or two together in the same direction it exposes a large area by which weeding is facilitated, it is cheaper than previous constructions and the labor cost of operation is reduced by fifty per cent.

This application is a continuation-in-part of my application, Serial No. 222,471, filed August 1, 1938.

Having thus described my invention, I claim:

1. In hot frame constructions, walls defining a hotbed and forming an upper opening, a plurality

of sashes extending transversely of the bed supported on the walls to cover said opening and arranged for sliding movement relative to and on each other and to the walls, and complementary overlapping means preventing lateral separation of said sashes during such sliding movements.

2. In hot frame constructions, walls defining a hotbed and forming an upper opening, a plurality of sashes extending transversely of the bed supported on the walls to cover said opening and arranged for sliding movement relative to each other and to the walls, and means holding the sashes laterally together during such sliding movements, said means comprising complementary overlapping interlocking lips and grooves.

3. In hot frame constructions, walls defining a hotbed and forming an upper opening, a plurality of sashes extending transversely of the bed supported on the walls to cover said opening and arranged for sliding movement relative to each other and to the walls, and means holding the sashes laterally together during such sliding movements, said means comprising complementary interlocking lips and grooves mounted on the respective sash, the groove on one sash being vertically aligned with the lip on the other sash.

4. In hot frame constructions, walls defining a hotbed and forming an upper opening, a plurality of sashes extending transversely of the bed supported on the walls to cover said opening and arranged for sliding movement relative to each other and to the walls, and means comprising complementary interlocking lips and grooves on the respective sashes forming in overlapped relations and interlocking connection holding the sashes laterally together during such sliding movements, one sash resting upon an adjacent sash through its interlocking connection on one side and supporting the edge of the next adjacent sash on the other side.

5. In hot frame constructions, walls defining a hotbed and forming an upper opening, a plurality of sashes extending transversely of the bed supported on the walls to cover said opening and arranged for sliding movement relative to each other and to the walls, and overlapping means holding the sashes laterally together during such sliding movements, the last mentioned means including inclined meeting surfaces so arranged that the weight of one sash applied through the connection forms an automatic take up between said sashes to compensate for any warping.

6. In hot frame constructions, walls defining a hotbed and forming an upper opening, a plurality of sashes extending transversely of the bed supported on the walls to cover said opening and arranged for sliding movement relative to each other and to the walls, and means holding the sashes laterally together during such sliding movements, the last mentioned means including lips and grooves on respective sashes at least one having inclined meeting surfaces so arranged that the weight of one sash applied through the connection retains sealing engagement between the lips and grooves of contiguous sashes despite limited lateral relative movements of said sashes.

7. A sash for hot frames comprising a framework having lateral parallel side frame members, each of the latter being undercut longitudinally full length at the outer edge with each undercut of the same depth, one frame undercut to present a longitudinal guide surface sloping upwardly and the other presenting a longitudinal guide surface sloping downwardly, said upwardly and downwardly presenting surfaces being duplicate

complements and extending across a plane median of the sash; said sash so constructed and arranged as to engage adjacent sash of a series of similar sash in laterally overlapping interlocking and endwise sliding guided relation substantially in the plane of the sash.

8. In hot frame constructions, walls defining a hotbed having an upper opening, a plurality of sashes extending transversely of the bed supported on the wall to cover said opening and arranged for sliding movement relative to each other and to the walls, overlapping means holding the sashes laterally together during such sliding movements, lateral guide means rigid with the frame for engaging and interlocking with the first sash of a series to anchor same while permitting free sliding thereof parallel to said guide means.

9. A propagating bed comprising a skeleton frame open at the top and bottom, a strip transversely disposed across one end thereof having an undercut groove forming a downwardly located

lip along the inner side of said rail, a sash having grooves respectively in the stiles thereof, said grooves forming an upwardly disposed lip along the outer face of one stile and a downwardly disposed lip along the outer face of the other stile, 5 said upwardly disposed lip being arranged to telescope with the groove of said rail, and a second sash provided with upwardly and downwardly disposed lips along the respective sides thereof, the upwardly disposed lip thereof being arranged 10 to telescope with the downwardly disposed lip groove of said first sash, whereby said second sash is anchored by the weight of said first sash.

10. In a propagating frame, a plurality of sashes forming the top thereof, telescopic overlapping laterally gravitationally secured joints for interconnecting one sash with another, and telescopic lateral joint means on said frame overlapping adjacent sashes for permitting endwise displacement of said sashes. 15

EUGENE P. LEEPER. 20
